UNITED STATES PATENT OFFICE.

IRA FILSON, OF SPRINGFIELD, OHIO.

AUTOMATIC ALARM.

No. 836,377.

Specification of Letters Patent.

Patented Nov. 20, 1906.

Application filed February 8, 1905. Serial No. 244,706.

To all whom it may concern:

Be it known that I, IRA FILSON, a citizen of the United States, residing at Springfield, in the county of Clark and State of Ohio, have 5 invented certain new and useful Improvements in Automatic Alarms, of which the following is a specification, reference being had therein to the accompanying drawings.

This invention relates to automatic alarms, 10 being designed primarily for use in connection with stoves, furnaces, or other heating apparatus employing gaseous fuel, and particularly natural gas, where danger arises in case of a temporary failure of the fuel-supply, 15 although the invention is capable of use in other connections.

The primary object of the invention is to provide an apparatus which will give an alarm in case of any material interruption of 20 the fuel-supply, so as to permit the taking of the necessary steps to prevent the escape of unburned gas in case the fuel-supply is reestablished.

Other objects of the invention are to provide a simple efficient apparatus of this character which may be readily applied to a heating apparatus already in use, which may be readily adjusted to meet the varying conditions, and which may be controlled to render 30 it operative or inoperative from different points either at the heating apparatus or at a distance therefrom.

To these and other ends my invention consists in certain novel features, which I will 35 now proceed to describe and will then particularly point out in the claims.

In the accompanying drawings, Figure 1 is a perspective view illustrating an apparatus embodying my invention in one form, the 40 same being shown applied to the smoke flue or pipe of a stove or furnace. Fig. 2 is a plan section of the same, taken above the apparatus proper. Fig. 3 is a vertical sectional view of the same, taken on the line xx of Fig. 45 1 and looking in the direction of the arrows. Fig. 4 is a detail sectional view illustrating the connection of the bracket to the pipe. Fig. 5 is a detail elevation of a portion of the pipe, showing the form of the aperture therein, the vane-bearing arm being shown in position 50 therein and in transverse section; and Fig. 6 is a perspective view of the locking slide or latch detached, by means of which the apparatus may be positively and mechanically locked in inoperative position.

Referring to the construction chosen for

purposes of illustration, which shows the apparatus applied to the ordinary sheet-iron smoke-pipe of a stove or furnace, 1 indicates the pipe, which may be a section of a stove- 60 pipe already in place or may be a separate section adapted for insertion therein. In this pipe there is formed an opening 2 in the wall thereof for the passage of the vane-bearing arm 3, which is pivotally mounted 65 in said opening. The connection may be formed in any approved manner; but I prefer the construction shown, in which the opening 2 is enlarged at its lower part, as indicated at 4, and has extending upward from its lower 70 margin a projection 5, formed of the sheet metal of the pipe. The opening 2 communicates at its upper end with a considerably larger opening 6 through the wall of the pipe. The arm 3, in the form of an inverted V in 75 cross-section where it passes through the pipe, so as to straddle the projection 5, and its diverging parts 7 are of greater length than the projection and are cut away on each side, as indicated at 8, to straddle the 80 wall of the pipe on which they rest as a fulcrum and prevent displacement of the arm in a longitudinal direction, the projection 5 preventing lateral displacement. That portion of the arm 3 lying immediately outward 85 from the inverted-V-shape portion 7 is of less width than the upper part of the opening 2, as indicated at 9, so that the arm can be removed from the pipe through the upper end thereof by first moving the arm upward 90 and inward until the part 9 thereof can be passed up through the upper part of the opening 2, thereby bringing the arm up into the larger opening 6, through which said arm and its counterweights may be readily passed 95 in an upwardly-inclined direction.

The arm 3 is provided within the pipe 1 with a vane 10 of a diameter somewhat smaller than the internal diameter of the pipe. At its other end the arm 3 is counterweighted, and in the present instance I have shown the counterweighting as effected partly by a fixed counterweight 11 in the form of a block secured to the arm 3 and partly by an adjustable counterweight 12 in 100 the form of a screw threaded in the block 11 and movable in the direction of the longitudinal axis of the arm, so as to adjust the relationship of the weights carried by the arm on the opposite sides of its pivot. Normally 105 these weights are so adjusted that the vane is slightly heavier than the counterweighting,

and the portion of the arm outside of the pipe tends to rise when the vane moves downward within the pipe, the action of said counterweights being sufficient to permit the

5 vane to rise in the pipe when the products of combustion in the stove or furnace to which the pipe is connected pass through said pipe or when currents of heated air similarly pass through said pipe. The counterweights are 10 of a size sufficiently small to permit them to pass through the opening 6.

13 indicates a bracket on the outside of the pipe 1, preferably in a position such as to cover the opening 6 and prevent said opening

15 from affecting the draft of the stove or furnace or permitting the escape of the products of combustion. This bracket is preferably secured to the pipe in the manner shown in detail in Fig. 4, in which each end of the

20 bracket is secured to the pipe by means of a screw-bolt 14, extending through an aperture in the pipe and having its head 15 located inside the pipe, which is clamped between said head and a nut 16 on the body of

25 the screw-bolt, a washer 17 being interposed between the head and pipe, if desired. The bracket 13 is provided near each end with a vertical open-mouthed slot 18, by means of which it may be slipped down over the projecting ends of the bolts 14 and clamped in

30 position against the nuts 16 by means of nuts 19, mounted on the bolts outside of the bracket. By reason of this construction the bracket may be readily applied to and re- 35 moved from the bolts, it being sufficient to merely loosen the nuts 19 to permit the bracket to be slipped out by an upward movement or as readily replaced. The bracket has outwardly-extending arms 20,

40 between the ends of which and above the arm 3 is stretched a wire 21, of conducting material, preferably copper, supported at its ends by insulating-blocks 22, to which it is connected. This wire forms one contact- 45 terminal of an electric circuit 23, comprising a battery or other source of electricity 24 and an alarm 25, preferably in the form of an audible bell or gong. This circuit also prefer- 50 ably contains a switch 26, by means of which

55 it may be opened or closed.

In practice the signal may be located at any desired point—as, for instance, in a bedroom located at a considerable distance from the stove or furnace. Similarly the controlling- 60 switch 26 may be located at any desired point, although preferably its location will be near the alarm, so as to permit it to be shut off by breaking the circuit as soon as it has accomplished its object by attracting attention. The other contact-terminal of the circuit 23 is the arm 3, to which the circuit-wire is connected in any suitable manner.

65 In the present instance I have shown the pipe 1 as forming part of the circuit, the wire being connected thereto at 27 in any suitable

manner, the arm 3 being of conducting material and being included in the circuit by reason of its contact with the pipe at its bearing thereon.

28 indicates a locking slide or latch for 70 positively and mechanically holding the arm 3 in position such as to prevent its operating the alarm. This slide is mounted on the exterior of the pipe 1, around which it slides transversely with respect to the arm 3, being 75 guided in any suitable manner—as, for instance, by a slot 29 in the slide and bolts 29^a, secured to the pipe. This slide is provided at one end with a projecting finger-piece 30, by means of which it may be readily operated, its other end being provided with diverging arms 31, which when the latch is projected past the arm 3 will engage said arm from above and below, respectively, and will hold it fixed in inoperative position.

85 The operation of the apparatus is as follows, assuming that it is applied to a stove or furnace using natural gas as a fuel: As long as the gas-supply continues and is being consumed the heated products of combustion pass through the pipe and will act upon the vane 10 so as to move the same upward and keep the arm 3 from contacting with the wire 21. If the supply of gas ceases only for a brief period and then re- 90 sumes its flow and the stove or furnace is provided with a filling of material heated by the gas, which filling will retain its heat for some time and will reignite the gas if the flow begins again sufficiently soon, then 95 the alarm will not operate, since the heated air passing through the pipe will act on the vane in the same manner as the products of combustion when the gas is burning; but if the period of suspension of flow is too long to 100 effect the reignition of the gas or if the stove or furnace has no reignition means then when the products of combustion or heated air cease to flow through the pipe the over- 105 weight of the vane will cause that end of the arm to which it is attached to fall and the other end will rise, bringing the arm 3 into contact with the wire 21. This will close the electric circuit and sound the alarm, thereby giving notice of the danger from 110 the flow of non-consumed gas. One material advantage of the particular construction shown is that since the arm 3 is so balanced as to be very sensitive, while the wire 21 is more or less resilient, the alarm is at first 115 an interrupted one, the circuit being alternately closed and opened at successively decreasing intervals until it finally remains closed. This initial interrupted or spasmodic action is in practice more efficient in attracting notice than a continuous alarm. As 120 already stated, the alarm can be cut off as soon as it has accomplished its purpose by means of the switch 26. The same result can be obtained at the stove or furnace itself by 125

130

means of the slide 28. This slide, however, is primarily intended to lock the arm 3 in inoperative position when the stove or furnace is not in use—as, for instance, during the summer.

It will be seen that the structure is inexpensive and can be readily applied to the pipe of a stove or furnace already in place, and its application and removal are readily effected.

While the construction which I have illustrated and described is that which I prefer, it is obvious that modifications may be made without departing from the principle of my invention, and I therefore do not wish to be understood as limiting myself strictly to the precise details of construction hereinbefore described, and shown in the accompanying drawings. It is also obvious that the invention is capable of other applications and adapted for use in other connections than the specific ones set forth.

Having thus fully described my invention, what I claim as new, and desire to secure by Letters Patent, is—

1. The combination, with a support provided with a vane, an electric circuit comprising a source of electricity, an alarm and a fixed contact-terminal located in the path 30 of the arm, said arm constituting the other contact-terminal of said circuit, and means for positively and mechanically locking said arm in inoperative position, substantially as described.

2. The combination, with a support, of a pivoted arm provided with a vane, an electric circuit comprising a source of electricity, an alarm, a circuit-controlling switch and a fixed contact-terminal located in the path 40 of the arm, said arm constituting the other contact-terminal of said circuit, and means for positively and mechanically locking said arm in inoperative position, substantially as described.

3. The combination, with the outlet-pipe 45 of a stove or furnace, of an arm pivotally

supported thereon, extending through the wall thereof and provided with a vane within the pipe, an electric circuit comprising a source of electricity, an alarm and a fixed 50 contact-terminal located in the path of the arm, said arm constituting the other contact-terminal of said circuit, and a locking device mounted on said pipe and movable into engagement with the arm to maintain 55 it in inoperative position, substantially as described.

4. The combination, with the outlet-pipe of a stove or furnace, of an arm pivotally mounted thereon, extending through the wall 60 thereof and provided with a vane within said pipe, a bracket mounted on said pipe and having arms, a wire of conducting material stretched between said bracket-arms in the path of the vane-bearing arm, and an electric 65 circuit comprising a source of electricity and an alarm and having its ends respectively connected to said wire and vane-bearing arm, substantially as described.

5. The combination, with a pipe-section 70 having in its wall an aperture enlarged at its lower end and provided with an upwardly-extending projection, and a second aperture of larger diameter communicating with the restricted portion of said first-mentioned 75 aperture, of an arm provided with a vane at one end and a counterbalance at the other end, the latter of less size than the larger aperture in the pipe, said arm being of inverted-V shape in cross-section at its fulcrum-point, with its lateral portions cut away to straddle the pipe-wall, and of a width outward from its fulcrum portion to pass through the restricted portion of the opening 80 in the pipe, substantially as described. 85

In testimony whereof I affix my signature in presence of two witnesses.

IRA FILSON.
